WRINGER

Nicholas L. Etten, Waterloo, Iowa, assignor to
 Chamberlain Corporation, Waterloo, Iowa, a
 corporation of Iowa

Application August 11, 1945, Serial No. 610,235

4 Claims. (Cl. 68—253)

1

This invention relates to a wringer adapted for use in connection with a domestic washing machine and having operative mechanism for separating the rolls in the event of accidental insertion of the hand or other objects between the bite of the rolls.

This wringer embodies the use of a lower roll which rotates upon a fixed axis and incorporates suitable link-connected mechanisms for releasing the upper roll bodily and for moving its roll shaft away from the lower roll and in parallel relation thereto.

One of the main objects of the present invention is to provide such a wringer with the usual roll control operating handle connected with the gear driven mechanism for driving the rolls and by incorporating an interlocking mechanism directly connected with this handle to automatically move the same into neutral position for shutting off the roll drive whenever the wringer release mechanism is operated.

Another object of the present invention is to provide drive interrupting mechanisms functioning directly with the wringer roll release means to automatically cut off the drive to the wringer rolls regardless of the position of the wringer operating control handle.

In connection with the object immediately above, it is a further object of the present invention to provide such a drive interrupting means which also functions to disconnect the transmitted driving torque from the main drive shaft of the wringer thereby permitting the interlock means for returning the operating handle of the wringer to neutral position to function freely independently of frictional binding of the torque transmitting parts. Obviously, to operate the handle when the same is in one of its operating positions or the other depending upon the direction of rotation of the wringer rolls, it would take considerable effort to swing this handle into neutral position under the action of the power driving torque. By relieving the driving torque it is possible to introduce a light-weight mechanism comprising the interlock means for turning the handle the angular amount necessary to place the same into neutral or non-driving position thereby increasing the efficiency and effectiveness of such interlock means and also making such means economically practical.

Another object of the present invention is to provide suitably connected and arranged mechanisms for automatically reestablishing the power drive mechanism to operative driving position with respect to the main drive shaft and also to render the interlock means ineffective to permit

2

the wringer handle to again be manually actuated for operating the wringer rolls in the usual manner.

All other objects and advantages that are present in the preferred construction of wringer herein disclosed shall hereinafter be pointed out and become apparent from the following detailed description of such wringer having reference to the accompanying drawings.

In the drawings:

Fig. 1 is a side elevational view of the main operating mechanism as arranged in a preferred construction of wringer, some of the parts having been omitted and others being broken away and in section to better illustrate certain details thereof;

Fig. 2 is an end elevational view of the wringer illustrated in Fig. 1 as viewed from the post end of the wringer;

Fig. 3 is a vertical axial sectional view illustrating the torque release structure embodied in the present form of wringer drive;

Fig. 4 is a transverse cross sectional view thereof taken along the line 4—4 in Fig. 3 and looking in the direction indicated by the arrows;

Fig. 5 is a fragmentary plan view of the wringer structure and associated mechanism and of the left-hand end of the wringer with reference to Fig. 1;

Fig. 6 is another fragmentary plan view of the wringer structure showing the mechanism associated with the post end of the wringer; Figs. 5 and 6 when taken together substantially comprising a complete plan view of the entire wringer structure; and

Fig. 7 is an end elevational view of the wringer mechanism as viewed from the left hand end of Fig. 1.

Referring now to Fig. 1, the main body of the wringer comprises generally the pedestal 1 connected with or forming an integral part of the gear case 2 together with a sheet metal framework 3 suitably connected with the gear casing 2. The sheet metal framework 3 briefly comprises a right hand end channel structure 4 and a left hand end channel structure 5 as viewed in

Fig. 1, such structures being connected by a bottom trough 6 with stability and further strength provided by means of an overhead frame 7 connecting between the divided wringer shrouds 8 and 9. The foregoing elements provide the main body of the wringer and this unit as a whole is mounted by means of the pedestal 1 upon the wringer column. Appropriate indexing means 10 is connected with such pedestal to

lock the wringer in certain predetermined an-

gular positions with respect to the wringer column or post.

As further seen in Fig. 1, the drive is transmitted to the wringer rolls by means of the main drive shaft 11 connectible through the shiftable clutch 12 toward either one or the other of the driving pinions 13 and 14 which are rotatably carried upon the drive shaft 11 and suitably held against axial displacement with respect thereto. Pinions 13 and 14 connected with the crown gear 15 which is suitably connected with the roll shaft 16 by a pin 17 engaging the driving sleeve 18 to transmit the power drive to the lower wringer roll 19. Obviously, the drive from the lower roll will be frictionally transmitted to the upper roll 20 in the usual fashion.

An operating control handle for the wringer roll drive is indicated at 21 connected with a stub shaft 22 provided with an eccentric pin arrangement 23 having cooperative engagement with the annular groove 24 formed in the body of the clutch 12.

The upper end of the drive shaft 11 is journaled in a suitable bearing in the gear box 2 and is provided with the mechanism best illustrated in Figs. 3 and 4. Shaft 11 is counterbored as shown at 25 to slideably receive an actuating rod 26 having a large diameter portion 27 and a small diameter portion 28. The intermediate portion of the operating rod 26 is tapered as at 29 for cooperating with the locking balls 30 that are suitably carried or guided in radially drilled openings 31 formed in the main drive shaft 11.

The shiftable clutch 12 is longitudinally grooved at 32 to coact with the respective balls 30 so that under normal operating conditions the power drive from shaft 11 is transmitted through the balls 30 which are maintained in locked position within the grooves 32 of the clutch 12 whenever the operating rod 26 is in the lower longitudinal position illustrated in Fig. 3 and as shown in respect to the main drive shaft 11 that has no longitudinal movement. Whenever the operating rod 26 is moved vertically in the direction of the arrow 33, the balls 30 will no longer be held in their radially outward locations with respect to the shaft 11 and therefore will be actuated radially inwardly off of the tapered sides of the slots 32 as best comprehended from Fig. 4 and will move into the drilled openings 31 within the main drive shaft 11. This action discontinues the drive from the shaft 11 to the clutch 12 permitting the shaft 11 to revolve within its bearings in the gear box 2 and discontinuing power torque transmission to any of the other parts hereinbefore described in connection with the roll drive mechanism.

As seen in Fig. 1, this torque relieving operating rod 26 is held in its operative position as shown at Fig. 3 by means of the channel shaped arm 34 which is pivotally carried upon the pin 35 extending between the ears 36 forming a part of the gear box 2. The arm 34 bears against a reduced head portion 37 forming an integral part of the operating rod 26, the arm 34 holding the entire operating rod 26 downwardly against the action of the spring 38 interposed between the cup washer 39 and the bearing boss 40 of the gear box 2.

The arm 34 is normally held in its lowermost position as viewed at Fig. 1 by means of pins 41 secured to discs 42, such pins 41 engaging lateral lugs 43 formed as a part of the depending links 44 connected with the arm 34.

The discs 42 are spaced laterally with respect to the vertical median plane of the wringer as best illustrated in Figs. 2 and 6 and are mounted

upon a horizontally disposed shaft 45 suitably connected for rotation on the wringer frame. One of the discs is notched at 46 to cooperate with the roller 47 carried on the end of an arm 48 pivoted from the roll frame at 49 and normally urged against the disc 42 by means of a suitable spring at 50.

The vertical arm 51 carrying suitable hand release means such as the knob 52 is also secured to the arm 48 to operate above the pivot 49 for the purpose of moving the roller 47 out of engagement with the notch 46 of the disc 42 carrying such notch. Obviously, the arms 48 and 51 can be considered as a bell crank for all practical purposes providing a release means having trigger precision.

Attention is directed to the fact that both of the operating mechanisms disposed at the lateral sides of the wringer and extending the length thereof are duplicates and that the same reference numerals have been used to indicate like elements except where otherwise indicated. Continuing this description and referring to Figs. 1 and 2 it will be seen that links such as 53 are connected by means of pins 54 operating within slots 55 in the discs 42 and extend to connect with pins 56 carried by the bell cranks 57 that are pivotally mounted upon the wringer frame suitably supported from shaft 58. A pair of springs 59 connect between arms 60 of the bell crank 57 and lugs 61 formed upon the bell crank 62, the latter being pivotally guided within the slots 63 of the wringer frame by means of pins 64 in the manner best shown in Fig. 1. One end of the shaft 65 of the upper wringer roll 20 extends into the vertically movable bearing 66 which is pin connected at 67 with the bell crank 62 and such pins also extend through and are guided within the vertical slots 68 provided in the channel frame member 4.

Thus, as long as the springs 59 are suitably attached by means of the latched discs 42 through the instrumentality of the arms 53 and the connected bell cranks, the roll shaft 65 will press the upper roll 20 firmly against the lower roll 19 establishing an operative condition between such wringer rolls.

The mechanism at the far end of the wringer is very much the same as that described in connection with the post end of the wringer. Operative connection is established from the right hand roll tensioning mechanism in Fig. 1 to the left hand roll tensioning mechanism by means of the longitudinal links 70 which are pivotally connected at 71 to the bell cranks 57 and by means of pins 72 to bell cranks 73 pivotally carried at 74 from the wringer frame channel portion 5. Springs 75 are interposed between the pins 76 of the bell cranks 73 and the lugs 77 formed as an integral portion of the bell crank 78. The latter carries the pivot pins 79 for operation within the slots 80 formed in the brackets 81 secured to the channel section 5 of the wringer frame.

The upper roll shaft 65 also projects from the above described end of the roll 20 to enter the movable bearing 82 which is pivotally connected at 83 with another arm portion of the bell crank 18, such pivot pin at 83 also extending through and operating within the vertically disposed slot 84 formed in the sides of the channel frame 5.

Therefore, it is seen that any clockwise rotation of the discs 42 is permitted by means of the latch mechanism consisting of the bell crank arrangements incorporating arms 48 and 51 allowing the links 53 to rotate the controlling bell

cranks 57 and 73 to automatically release the springs 59 and 75 thereby permitting the upper roll to separate at the instant of the spring release from the lower roll 19 by parallel motion with respect to the lower roll which has no other movement than rotation upon the lower shaft 16.

Referring back to Fig. 1 it is seen that whenever the hand release knob 52 is operated that the discs 42 revolve in a clockwise direction carrying the pins 41 directly therewith and in the same direction. Whenever this happens the arm 34 will be urged upwardly by means of the spring 39 through the knob or head portion 37 of the operating rod 26 that releases the drive from the main shaft 11 to the clutch 12 and in automatic synchronism with the release of the wringer rolls as described before. It is also desirable that the operating control handle 21 for regulating the drive mechanism to the rolls should be disposed in neutral position whenever the wringer release mechanism has been operated. Furthermore, this main control handle 21 should also be locked in the neutral position whenever the rolls 19 and 20 have been parted through release in the event of accident inasmuch as this will prevent anyone from shifting the handle 21 to cause the lower roll 19 to begin to operate until the wringer is completely reset for operation.

This characteristic of the wringer is accomplished by the mechanism illustrated in Figs. 1, 2 and 3. A suitably formed bracket 85 is arranged for connection with the washer 39 and head 37 of the operating rod 26 and extends downwardly toward the handle shaft 22. As seen in Fig. 2, the lower end of the bracket 85 is slotted at 86 to be vertically guided by means of the flattened sides 87 of the boss 88 forming a portion of the gear box 2. A cam 89 is secured to the handle shaft 22 for movement directly therewith and such cam 89 may occupy the position shown in Fig. 2 when the handle is moved as shown in dotted lines for operating the wringer rolls in one direction, the cam 89 being moved into vertical position in Fig. 2 when the clutch 12 is to be moved into neutral position. The cam will occupy a position 180° to that indicated in Fig. 2 when the wringer rolls are to be reversed.

In any event the bracket 85 carries ears 90 and 91 for engaging the under sides of the cam 89 respectively depending upon the location of the cam with respect to the longitudinal vertical median plane of the wringer. In either case, the handle will be brought into neutral vertical position by either one of the lugs 90 or 91 engaging the sides of the cam 89 whenever the release knob 52 is operated causing the bracket 85 to move vertically under its connection with respect to the actuating rod 26 and under the action of the spring 39. Inasmuch as the torque release mechanism illustrated in Figs. 3 and 4 operates upon release of the wringer roll, the torque binding or frictional contact is eliminated between the drive shaft 11 and the clutch 12. Therefore, the bracket 85 and its associated mechanisms adapted to function so as to move the handle 21 into neutral position are of light weight construction and are efficiently operable and economical to manufacture.

In addition to the bracket 85 rotating the handle 21 into neutral position, the bracket is also provided with a latch lug 93 that is adapted to enter the notch 94 formed in the cam 89. This provides an appropriate locking means to lock the shaft 22 against operation until such a time

as the wringer is reset with the rolls 19 and 20 in operative squeezing contact.

There are various ways in which the disc shaft 45 may be rotated to bring the entire mechanism back into normal operating condition after the wringer has been released. The preferable arrangement and construction for resetting the wringer is illustrated in Fig. 2 and incorporates the use of a handle 95 loosely mounted upon the extended end 96 of the shaft 45 by means of the pin and groove connection 97. It is obvious that a handle of considerable length will better act to reset the wringer mechanism against the spring tension than a handle relatively short with a lower mechanical advantage. However, it is not desirable to provide a handle of this type which will whip about its axial center whenever the spring release mechanism operates as in this case where the shaft 45 substantially rotates 180° with trigger timing under the action of the springs 59 and 75.

It is for this reason that the handle is connected by means of the pin and groove connection 97 and furthermore carries a lug 98 for engagement with the pin 99 secured to the extension 96 of the shaft 45. A torsion spring 100 is connected at 101 with the shaft 96 and has an extended end 102 operating within a slot 103 formed in the extension lug 98 of the handle 95. This establishes a soft connection between the rotatable shaft 45 and the handle 95 permitting the shaft 45 to execute a quick 180° release while the spring 100 gradually picks up the handle 95 to slowly move the same in a direction away from the pin 99 and into some angular position with respect to the vertical position previously occupied by the handle. Thereafter, by moving the handle in a direction so that the lug 98 engages the pin 99 it is possible to rotate the shaft 45 in a counterclockwise direction until the discs 42 are moved into a position where the notch 46 will again relatch against the roller 47 of the release bell crank mechanism. This counterclockwise rotation of the discs 42 will also cause the pins 41 to re-engage the lugs 43 to pull the arm 34 downwardly into the position illustrated in Fig. 1.

This action also moves bracket 85 downwardly to disengage the lug 93 from the notch 94 in cam 89 to free handle 21 to again operate the clutch 12. The latter is also operatively connected to the drive shaft 11 by the return of the discs 42 since the operating rod 26 again forces the balls 30 radially into driving relationship with the grooves 32 of the clutch 12.

Variations and modifications in the exact structure herein shown and described are contemplated as well as the substitution of equivalent mechanisms. The language of the appended claims will govern the extent of such changes and the permissible variations.

What I claim is:

1. In a wringer, frame means including a fixed top bar, separable rolls therein, pressure mechanism for said rolls, drive means to actuate said rolls, clutch means between the rolls and said drive means, a pivoted arm controlling said clutch means, spring means biasing said arm toward released position to disengage said clutch means, lock means controlled by said arm to lock said clutch means in disengaged position when said arm is released, a rotary disk carried by said frame means, link means connecting said disk with said pressure mechanism, latch means engageable with said disk to hold the same against release in pressure applying position, means car-

ried by said disk to bear against said arm and hold the same in clutch engaging position, and means to disengage said latch means.

2. In a wringer, frame means including a fixed top bar, separable rolls therein, pressure mechanism for said rolls, drive means to actuate said rolls, clutch means between the rolls and said drive means, a pivoted arm controlling said clutch means, spring means biasing said arm toward released position to disengage said clutch means, lock means controlled by said arm to lock said clutch means in disengaged position when said arm is released, a rotary disk carried by said frame means, link means connecting said disk with said pressure mechanism, latch means engageable with said disk to hold the same against release in pressure applying position, means carried by said disk to bear against said arm and hold the same in clutch engaging position, means to disengage said latch means, and a handle to rotate said disk to pressure applying position, move said arm to clutch engaging position, and release said lock means.

3. In a wringer, a frame, a pair of rolls in said frame, tension springs each connected at one end to one of said rolls and extending beyond the other, link means having portions pivoted to said frame and connected to the other ends of said springs, a transverse shaft in said frame, a pair of spaced rotary disks on said shaft and connected with said link means to actuate the same to pressure applying position with said springs under tension, latch means to hold said disks in pressure applying position, drive means, clutch means to connect said drive means with said rolls, a pivoted arm to control said clutch means, means biasing said arm toward clutch disengaged position, and pins carried by said disks to bear on said arm and hold the same in clutch engaging position.

4. In a wringer, a frame, a pair of rolls in said frame, tension springs each connected at one end

to one of said rolls and extending beyond the other, link means having portions pivoted to said frame and connected to the other ends of said springs, a transverse shaft in said frame, a pair of spaced rotary disks on said shaft and connected with said link means to actuate the same to pressure applying position with said springs under tension, latch means to hold said disks in pressure applying position, drive means, clutch means to connect said drive means with said rolls, a pivoted arm to control said clutch means, means biasing said arm toward clutch disengaged position, pins carried by said disks to bear on said arm and hold the same in clutch engaging position, lock means connected to said arm to lock the clutch means in disengaged position, and a handle connected to said transverse shaft to reset roll pressure by rotating said disks whereby said arm is pivoted to clutch engaging position and said lock means are released.
